DESIGN FOR A DOLL OR SIMILAR ARTICLE

Catherine F. Reighard, New York, N. Y.

Application May 21, 1938, Serial No. 77,339

Term of patent 7 years

To all whom it may concern:

Be it known that I, Catherine F. Reighard, a citizen of the United States, residing at New York, in the county and State of New York, have invented a new, original, and ornamental Design for a Doll or Similar Article, of which the following is a specification, reference being had to the accompanying drawing, forming part thereof.

Figure 1 is a front elevation of a doll or similar article showing my new design; and

I claim:

The ornamental design for a doll or similar article, substantially as shown.

CATHERINE F. REIGHARD.
